CLAIM

The ornamental design for a self-balanced vehicle, as shown and described.

DESCRIPTION

FIG. 1 is a front side view of the design according to the invention.

FIG. 2 is a back side view of the design according to the invention.

FIG. 3 is a left side view of the design according to the invention.

FIG. 4 is a right side view of the design according to the invention.

FIG. 5 is a top side view of the design according to the invention.

FIG. 6 is a bottom side view of the design according to the invention; and,

FIG. 7 is a perspective view of the design according to the invention.
